UNITED STATES PATENT OFFICE.

HENRY C. WILLIAMSON AND HERMAN PRIES, OF MICHIGAN CITY, INDIANA.

DRAFT-RIGGING.

SPECIFICATION forming part of Letters Patent No. 741,948, dated October 20, 1903.

Application filed September 10, 1903. Serial No. 172,642. (No model.)

To all whom it may concern:

Be it known that we, HENRY C. WILLIAMSON and HERMAN PRIES, citizens of the United States, and residents of Michigan City, county of Laporte and State of Indiana, have invented certain new and useful Improvements in Draft-Rigging, of which the following is a specification, and which are illustrated in the accompanying drawings, forming a part thereof.

This invention relates to that class of draft-rigging for railway-cars in which the cushioning or buffing springs are supplemented by friction; and its object is to simplify and increase the efficiency of devices of this character.

The invention consists of the parts and arrangement of parts as illustrated in the accompanying drawings, in which—

20 Figure 1 is a side elevation of the draft-rigging, a detail section of a railway-car being shown. Fig. 2 is a plan section on the line 2 2 of Fig. 1. Fig. 3 is a transverse section on the line 3 3 of Fig. 2, and Fig. 4 is a 25 similar section showing a modified form of construction.

In devices of this kind the object in view is the absorption of pressure by the combined agency of springs and frictionally engaging 30 parts and its transmission through these agencies to the car. In the present instance the pressure applied to the springs is in part transmitted directly to the car and in part indirectly by being utilized in increasing the 35 friction between the sliding parts.

The drawings show at 10 cross-timbers of a car and at 11 longitudinal or draft timbers, cheek-plates 12 being applied to the latter in the usual manner. A pair of followers 13 14 40 engage the forward and rearward shoulders of the cheek-plates and are acted upon by a draw-bar 15, having a tailpiece, shown as taking the form of a loop 16, which incloses the followers and the cushioning mechanism. 45 Two sets of cushioning-springs 17 18 are employed, one seated against each of the end followers. A plunger 19 is interposed between the two sets of springs and has a stem 20 extending along the axis of one set of 50 springs and reaching normally almost but not quite to the follower 13, against which the spring is seated. A circumferential flange

21 projects from the opposite face of the plunger 19, inclosing the spring 18, but not being of sufficient length to normally reach to the 55 end follower 14, against which this spring is seated. A plurality of friction-plates 23, preferably segmental in form, as shown in Fig. 3, engage the peripheral face of the flange 21. These plates have their ends beveled, 6c as shown at 25 26. A third follower 27 is interposed between the plunger 19 and the spring 17 and is apertured to accommodate the stem 20 of the plunger. Preferably, though not necessarily, the face of the plunger engaging the follower 27, is inclined, and the aperture of the plunger is correspondingly formed.

From adjacent faces of each of the followers 14 and 27 there projects a circumferential 70 flange 28 29, the inner faces of these flanges being beveled or inclined outwardly, as shown at 30 and 31, to correspond with the bevels 25 26 of the plates 23.

The action of the device is as follows: The 75 springs 17 18 maintain the plunger 19 and the follower 27 in contact, and there is such balance between these two sets of springs that the end of the stem 20 is prevented from contact with the follower 13. Forward draft 80 being applied, the tail-strap 16 carries the follower 14 forward, compressing both sets of springs until the stem 20 is brought into engagement with the follower 13. Further movement of the plunger being now rendered impossible, the further compression 85 of the spring 17 is accomplished by the movement of the follower 27, pressure being transmitted to it through the friction-plates 23, which slide upon the peripheral face 90 of the flange 21. The inclined faces of the flanges 28 29 and of the friction-plates force the latter inwardly toward the plunger, thereby increasing the frictional contact between these parts in proportion to the pressure applied. Upon release of the pressure 95 the various parts return to their normal position, the friction between the flange 21 and plates 23 being diminished as gradually as it was increased. The application of thrust-pressure produces like results. The plunger 19 is moved inwardly, compressing the springs 17 and 18. When the follower 13 comes in contact with the end of the stem 20, the 100

plunger is advanced, the periphery of its flange 21 sliding along the inner faces of the plates 23, and the frictional engagement of these parts is gradually increased by the 5 wedging action of the followers 27 and 14, as before.

Preferably the plunger and the flanges of the followers 14 and 27 are annular in form, in which case the friction-plates take the segmental form, as shown in Fig. 3. Any other form may be used, as, for example, shown in Fig. 4, wherein the plunger 22 and the follower 32 are shown as square and the friction-plates 24 as flat.

15 We claim as our invention—

1. In a draft-rigging, a pair of followers each having a peripheral flange having its inner face beveled, segmental plates having correspondingly - beveled ends and interposed between the followers, a plunger having its peripheral face in sliding engagement with the inner faces of the segmental plates, a spring reacting between the plunger and one of the followers, a stem projecting 25 from the plunger loosely through the other follower, a third follower, and a spring reacting between the third follower and the apertured follower.

2. In a draft-rigging, in combination, a pair 30 of followers having their adjacent faces inwardly beveled, plates having beveled ends fitted to the beveled faces of the followers, a plunger fitting loosely through one of the followers and having its periphery in sliding 35 engagement with the plates, a spring reacting between the plunger and the other follower, a third follower, and a spring reacting between the same and the apertured follower.

3. In a draft-rigging, in combination, a longitudinally - reciprocating plunger, friction- 40 plates engaging the periphery of the plunger, relatively approachable followers having wedging engagement with the outer faces of the plates, and an expansion-spring for separating the followers.

4. In a draft-rigging, in combination, a longitudinally - reciprocating plunger, friction-plates engaging the peripheral face of the plunger, means for advancing the plunger, and means for forcing the plates toward the 50 plunger.

5. In a draft-rigging, in combination, a central member, friction-plates in sliding engagement with the side faces thereof, followers connected with the central member and 55 plates so as to move them longitudinally in relatively opposite directions and having a compressive wedging engagement with plates.

6. In a draft-rigging, in combination, front and rear followers, a member between the 60 followers, springs interposed between the followers, friction-plates engaging the peripheral surface of such intermediate member, means for moving the plates and the intermediate member relatively in opposite directions, and means for moving the plates toward the intermediate member.

7. In a draft-rigging, in combination, a pair of end followers, an intermediate plunger, a pair of springs reacting respectively between each follower and the plunger, a stem projecting from the plunger toward one of the followers but normally not contacting therewith, a peripheral flange extending from the opposite face of the plunger, a follower engaging the face of the plunger and having an aperture for its stem, peripheral flanges extending from adjacent faces of the last-named follower and the end follower adjacent the plunger-flange, such follower-flanges having 75 their inner faces oppositely inclined, and friction-plates interposed between the follower-flanges and bearing against the peripheral flange of the plunger-flange.

HENRY C. WILLIAMSON.
HERMAN PRIES.
